UNITED STATES PATENT OFFICE.

WILLIAM P. CROCKETT, OF CHICAGO, ILLINOIS.

SHOULDERED NUT OR BUSHING AND METHOD OF MAKING SAME.

Application filed January 10, 1921. Serial No. 436,054.

To all whom it may concern:

Be it known that I, WILLIAM P. CROCKETT, a citizen of the United States, residing at Chicago, in the county of Cook and State 5 of Illinois, have invented certain new and useful Improvements in Shouldered Nuts or Bushings and Methods of Making Same, of which the following is a specification.

Nuts or bushings are known, particularly 10 for use in electrical fittings, having a threaded bore extending the major portion of the depth of the body, and having a shallow inwardly-extending annular flange forming a squared shoulder at the end of 15 the threaded bore, such flange providing a reduced opening the external edge portion, or mouth, of which is rounded in cross-section. For electrical wiring, such a bushing is used on the threaded end of a metallic 20 conduit where the latter enters an outlet box, switch box or the like, the threaded bore screwing onto the end of the conduit, the square shoulder contacting with the square-cut end of the conduit, and the 25 through opening of the internal flange forming an effective continuation of the bore of the conduit, while the rounded mouth of said flange gives the requisite non-cutting lip-surface to prevent the insulated 30 wiring from being chafed or injured. Also the base of such bushing forms a stop to be clamped against the inner wall of the outlet box by the action of a nut that is threaded on the conduit and screwed up 35 against the outer surface of the outlet box wall.

Such shouldered bushings have commonly 40 been made of one piece construction by casting the device in final form, or by forging or swaging a blank into the desired general form but with a smooth cylindrical bore, and then tapping or threading said bore. Neither process produces wholly satisfactory results. The casting operation 45 produces many poorly-threaded and otherwise defective pieces and rarely do the threads run full depth of the bore. The forging process is relatively expensive and difficult. Not only is it hard to thread the 50 bore with a full uniform thread extending clear to the shoulder, but in practice it is expensive in that each piece must be individually threaded, and furthermore, the forging or swaging of the blank is apt to 55 result in such hardening of the metal that the threading operation will wholly or

partly fail. It is common and time-waste- 60 ful experience to find on the market a material percentage of such bushings that will not screw home on the conduit and have to be discarded, oftentimes after so damaging the conduit-threads, in the effort, as to increase the trouble and time-waste.

One of the objects of my present invention is to provide an improved shouldered 65 nut or bushing of two-piece construction, and a method of making the same, insuring cheapness and uniformity of the product and perfection of the requisite bore-threading.

In the drawing wherein I have shown 70 my invention embodied in a bushing for the electrical use above described, but without intent to limit myself solely to such application of the invention, Fig. 1 is a vertical section through an outlet box and conduit fragment in association with a bushing embodying my invention; Fig. 2 is a section on line 2—2 of Fig. 1; Fig. 3 is an extended view schematically representing steps in the manufacture of my invention; Fig. 4 is a diagrammatic elevation with the parts in section showing a final 75 operation in the manufacture of the nut; and Fig. 5 is a section of a modified bushing embodying features of my invention.

In the construction shown 10 indicates the body element of the bushing, uniformly threaded throughout its bore-length, and 11 is a shallow shoulder-forming collar, or 80 ring, preferably externally threaded, located in the mouth end of the body-bore and there permanently set or retained as by substantially immovable frictional grip 85 brought about by forcing the parts together.

In the manufacture of the article shown 90 the bushing bodies are preferably stamped out of sheet metal of proper thickness into blanks, preferably of non-circular perimeter, such as the conventional hexagon shape shown, each with a smooth through bore, as indicated at 10^a in Fig. 3. These blanks are then internally threaded as at 10^b, Fig. 3, and since the threading preferably extends throughout the full-bore length of the blank the tapping operation may be done on a stack of blanks in a single pass of the tapping tool, schematically suggested at 12 in Fig. 3. The blank thus provided 100 may be in substance a deep nut of ordinary 105 form.

These bodies stand ready to receive the shoulder elements or rings 11, each of which, in its blank form is a square edged ring of a depth much less than that of the body blank, preferably externally threaded, and with a center opening substantially corresponding with or slightly less than the bore of the conduit with which the finished bushing is intended to be used. In making these 10 ring blanks I preferably use tubular stock of suitable size, thread the tube externally throughout its length as indicated at 11^a and saw off the ring blanks 11^b of suitable depth, preferably utilizing for this purpose a gang 15 of parallel saws 13. A ring blank 11^b is then screwed into the body blank 10 until their outer end surfaces are flush. In ordinary sizes of bushings this operation may most conveniently be done by the operator picking 20 the ring blank up on the tip of the finger and screwing it into the body blank until the thumb, exploring the joint, finds the parts to be flush. The assembled blanks are then presented to a setting device, which 25 may take the form of a simple punch member 16 and a coacting anvil 17, so that by a blow of the punch the collar ring is expanded radially and has its mouth rounded as at 10^c, the expansion of the ring setting it permanently in position in the body with a frictional grip that is (for all practical purposes of use) permanent or unbreakable. This operation may be done without distorting the thread 10^b exposed in the free 30 bore of the body, and so it is insured that the free bore-threading of the bushing is full and uniform throughout the intended conduit-receptive depth. Of course, superficial finishing, by way of enameling or 35 otherwise, is an optional matter following customary practice.

While a smooth or non-threaded ring of sufficiently malleable material may be expanded into the threads of the body, it is desirable to preliminarily thread the ring both to give facility of placing the ring accurately at the proper location in the body and to minimize the ring-expansion requirement.

Further, as shown in Fig. 5 the nut-blank 50 may have its mouth-end milled out, before or after threading, to form a socket 10^d and a ring 11^d exteriorly smooth, may be seated in the socket and thereafter the parts forced together permanently to set the ring, but 55 this, too, I deem much less advantageous than the construction first described.

While I have herein described in detail particular embodiments of my bushing invention and the method of making same, it 60 will be understood by those skilled in the art that various changes in detail may be

made without departure from the spirit of my invention within the scope of the appended claims.

I claim:

1. An article of the character described, comprising a body internally threaded throughout its free bore and a shallow solid ring permanently engaging throughout its side-surface in the mouth or end of said body-bore. 65

2. As an article of manufacture, a shouldered nut of the character described comprising a body having a uniform bore threaded throughout its bore-length and a shallow solid ring member externally threaded throughout its length and located wholly within the body-bore, the threads of the ring member engaging the end threads of the body member with a permanent frictional grip. 75

3. An article of the character described, comprising a body having a through-bore uniformly threaded throughout, a relatively shallow ring member externally threaded, having a squared in-facing shoulder and a rounded mouth, said ring member permanently and substantially non-removably seated in the end threads of the body bore with the ends of the body and ring substantially flush. 85

4. The method of making shouldered bushings which consists in providing a body with a cylindrical bore threaded throughout its free length, blanking a shallow solid ring of size to enter the mouth of the bore and expanding the ring in the bore-mouth to engage the body throughout the full depth of the ring. 95

5. The method of making shouldered bushings which consists in providing a body having a cylindrical bore threaded throughout its length, blanking a solid ring having an external thread to interfit with the bore thread, screwing the ring into the mouth of the body-bore, and expanding the ring into the body to fix the parts permanently against displacement. 100

6. The method of making bushings which consists in making a deep body-blank with its bore uniformly threaded throughout, making a shallow ring element externally threaded to engage said bore, screwing the shallow ring into the deep body until their end surfaces are substantially flush and by a subsequent forming-action rounding the mouth of the ring and also expanding the ring into permanent engagement with the body threads. 110

Subscribed and sworn to at Chicago, Illinois, this 10th day of December 1920.

WILLIAM P. CROCKETT,
